ELECTRICAL CONNECTOR HOUSING FOR POWER
LINE ELECTRICAL CONNECTORS

Robert Chieda, 3 Northgate, Westport, Conn.

Filed Feb. 5, 1964, Ser. No. 78,530

Term of patent 14 years

(Cl. D26—1)

FIG. 2

FIG. 1

FIG. 3

FIG. 4

FIG. 5

FIGURE 1 is a perspective view of an electrical connector housing for power line electrical connectors, showing my new design, which defines a hollow interior volume for receiving an electrical connector therein and may be seen to be substantially symmetrical about a vertical, longitudinal median plane.

FIGURE 2 is a top plan view of my housing design.

FIGURE 3 is a full side elevation view of this housing.

FIGURE 4 is a front end elevation view of this housing, the two parts of the housing being at least partially separable along the vertical median line, which appears in the drawing.

FIGURE 5 is a bottom plan view of this housing design.

I claim:

The ornamental design for an electrical connector housing for power line electrical connectors, substantially as shown and described.
